CLAIM

The ornamental design for a medical care system as shown and described.

DESCRIPTION

FIG. 1 is a front view of a medical care system of my design in a closed configuration;

FIG. 2 is a rear view thereof;

FIG. 3 is a top view thereof;

FIG. 4 is a right-side view thereof;

FIG. 5 is a left-side view thereof;

FIG. 6 is a front view thereof in an open configuration;

FIG. 7 is a rear view thereof;

FIG. 8 is a top view thereof;

FIG. 9 is a right-side view thereof;

FIG. 10 is a left-side view thereof;

FIG. 11 is a front view of another embodiment of my medical care system in a closed configuration;

FIG. 12 is a rear view thereof;

FIG. 13 is a top view thereof;

FIG. 14 is a right-side view thereof;

FIG. 15 is a left-side view thereof;

FIG. 16 is a front view thereof in an open configuration;

FIG. 17 is a rear view thereof;

FIG. 18 is a top view thereof;

FIG. 19 is a right-side view thereof;

FIG. 20 is a left-side view thereof; and,

FIG. 21 is a perspective view thereof.

The broken lines in the drawings depict portions of the medical care system that form no part of the claimed design.
